UNITED STATES PATENT OFFICE

2,007,495

PISTON

Alpheus Flower, London, England

Application March 7, 1933, Serial No. 659,970
In Great Britain March 9, 1932

11 Claims. (Cl. 309—14)

This invention relates to multi-piece pistons for fluid-pressure engines; and particularly to the bi-metallic kind comprising a crown or head formed of aluminium or other light alloy, preferably as a casting, with integral wrist-pin or gudgeon-pin bosses or other body parts to which is attached a tubular skirt of cast iron, steel, or some other good wear-resisting material.

The main object of the present invention is the provision of an improved method of and means for attaching the skirt to the head or some other piece of the piston whereby said means constitute a device for compensating for the varying expansion and contraction of the different metals. A further object is to provide an improved arrangement with which the cost of production will be reduced, particularly inasmuch as it allows of the head being cast independently of the tubular skirt and subsequently securely united to it in an inexpensive and simple manner.

Furthermore, in the usual type of "cast-in" bi-metallic pistons the contraction of the aluminium from its hot state, after the casting operation, provides a clearance between the two metals; that is, between the steel skirt and the bosses for the wrist-pins, etc., inside the skirt; and where the skirt meets the head or lower portion of the ring belt of the piston, or at the lower end of the skirt, the initial contraction clearance is too great and allows the head or other parts to move relatively to the steel skirt. A further object of this invention is to obviate this disadvantage.

A piston, according to the main feature of the invention, has a tubular skirt provided peripherally with a substantially flat disc or annular portion through which the skirt is attached to another piece of the piston.

According to a further feature of the invention, the inner periphery of the annular portion is surrounded by a flange which extends inwardly of the skirt and engages the other piece of the piston for attachment purposes. This flange may be frustum-shaped, with or without an outwardly-flared edge, or with or without a keying hole.

According to a still further feature, the steel skirt has a portion, preferably at the top or bottom thereof, originally enlarged in diameter externally, and after the metal of the head or other part of the piston has been cast and has cooled off the skirt is drawn through a ring of the desired final dimension of the skirt, or treated in an equivalent manner, thereby bringing the enlarged portion back to the proper diam-

eter. By this means the clearance between the exterior wall of the head or other part of the cast metal and the inner wall of the steel skirt can be reduced, thereby preventing any independent rocking of one part relatively to the other.

In the accompanying drawing:

Figure 1 is a vertical section through the wrist-pin or gudgeon-pin axis of one form of bi-metallic piston according to the invention;

Figure 2 is a cross-section on the line II—II of Figure 1;

Figure 3 is a corresponding cross-section showing a modification;

Figure 4 is a vertical section through part of another form of bi-metallic piston according to the invention;

Figure 5 is a fragmentary vertical section indicating another embodiment of the invention;

Figure 6 is a fragmentary vertical section, to a somewhat larger scale, indicating a step in the manufacture of the pistons shown in any of the foregoing figures; and

Figure 7 is a similar view to that of Figure 6, but it shows a modified arrangement.

Like numerals indicate like parts throughout the figures.

In the constructions illustrated in Figures 1 to 4, showing a bi-metallic piston having a head 2 of aluminium alloy, formed integrally with body webs 3, 3 from which the wrist-pin or gudgeon-pin bosses 4, 4 are supported, and a tubular skirt 5 of steel, the latter is provided peripherally, below where the wrist-pin will be, with a depression forming a substantially flat annular portion 6 the centre of which is in the longitudinal plane of the skirt through the wrist-pin axis.

In the arrangement of Figures 1 and 2, where there is a single flat annular portion 6 on each side, each of these has at its centre an aperture surrounded by a frustum-shaped flange 7, the end of which, in the interior of the skirt, is outwardly-flared, as at 8, to provide an increased keying effect with the circular metal boss 9, beneath the wrist-pin bosses 4, which is cast on to the flange 7.

Obviously the metal bosses 9 may be in the form of a belt 10 extending wholly, or partly, as shown in Figure 3, around the piston, and there may be two or more keying flanges 7 on each side of the piston, as is also indicated by Figure 3. The cast metal inside the flanges may be hammered into contact therewith after cooling.

This latter figure also shows a further method of securing the skirt through the annular portion 6 which may be used as an alternative to or

in conjunction with the arrangement of Figures 1 and 2. In Figure 3 the non-circular head of a bolt 11 is embedded in the belt 10 co-axial with the flange 7, and the latter contains a nut 12 of similar outline and adapted, as by the provision of serrations 13, to be screwed tightly on to the bolt after the cast metal has cooled and shrunk. Tightening the nut forces the flange into contact with the surrounding metal. The 10 nut can be locked by punching part of the bolt into the serrations 13.

In the arrangement of Figure 4 the head, as illustrated, is pre-cast and then bolted to the skirt at the flat annular portions 6 of the latter. 15 Thus, the metal of the body of the head is also formed with a more or less similar depression 14 that will engage the inner face of the flat annular portion 6 but be elsewhere spaced from the skirt, to allow of expansion of the head body. A 20 bolt 15 with a flat narrow head resting in the depression and not extending as far outwardly as the main portion of the skirt is passed through the skirt and through a corresponding hole in the body portion of the head. At its inner end 25 there is a nut 16 which can be tightened to lock the skirt and body portion securely together.

It is desirable to prevent relative rotation of the nut on the bolt, and for this purpose a disc washer 17 may be interposed between the nut 30 and the adjacent inner face of the body portion, the washer being formed with outwardly-extending tangs 18, 18 of which one enters a hole 19 provided in the under-surface of the wrist-pin boss 4 to prevent rotation of the washer, whilst 35 another tang can be bent up as shown to lock the nut after it has been tightened. In like manner suitable holes 20, 20 may be provided in the bolt and in the body portion to receive a short stem or key 21 by which the bolt, when the nut 40 is tightened, will be locked against rotation.

In a preferred arrangement the bolt is formed with an enlarged shoulder 22 beneath its head (which is conveniently the portion of the bolt drilled to receive the bolt locking member 21) 45 and this enlarged shoulder fits the hole in the skirt and extends into a corresponding recess provided in the body portion, acting to take the shear load.

As stated, in practice at least two such attachment means would be provided for a piston, these 50 being arranged diametrically opposite one another. To facilitate assembly, a longitudinal groove 23 is provided to receive the flat annular portion 6 and its internal flange 24, which springs into the hole in the head body.

In the modification of Figure 5, where the head is cast on to the skirt, the flat annular portion 6 and the flange 7 are co-axial with the wrist-pin bosses 4. This construction is some- 60 what lighter and cheaper to produce than that of Figures 1 and 2. The keying effect is increased by the provision of the holes 25.

With a view to preventing relative movement between the head of the piston and the upper 65 end of the skirt, these are preferably adapted in the manner illustrated in Figure 6 or Figure 7, where the clearances between the skirt and the cast metal are shown much exaggerated for the sake of clearness. There the skirt, prior to the 70 casting operation, is not of uniform bore; but at its upper and lower ends 26, 26 it is enlarged slightly, as indicated in Figure 6 or 7.

In the arrangement of Figure 6, where the skirt ends are enlarged both internally and externally, it follows that ridges 27, 27 are formed

on the cast metal in the vicinity of the skirt enlargements during the casting operation. When, however, the metal has cooled, the skirt is drawn through a die, or treated in other ways, such that the enlarged portions 26, 26 5 at its upper and lower ends are brought into line with the remainder of its surface, as indicated in Figure 1, where the upper end of the skirt is shown in very close proximity to the ridge 27.

Consequently, in spite of the fact that the cast metal of the head may shrink from the skirt, leaving an initial clearance, when finally treated the clearance between the upper or lower end of the skirt and the cast metal can be reduced to any requisite amount, and by this means movement between the ends of the skirt and the cast metal can be entirely prevented.

The most inexpensive method of producing 20 the skirt probably consists in the use of a skirt of uniform bore and thickness, of which the ends can then be enlarged to the necessary diameter, as described above, in connection with Figure 6. But an alternative method would consist in the use of a skirt of uniform bore and 25 greater thickness at the two ends 26, 26 as shown in Figure 7, these thickened portions constituting the skirt enlargements referred to above and being flattened, as by being drawn through a die, after the cast metal has cooled.

In all cases, after the enlargements have been flattened, the clearances there should be such as to allow of contact being made internally of the enlargements when the parts have expanded under the normal working temperatures.

It will be seen that by means of the invention a very firm and lasting attachment is evolved which compensates for the varying expansions of the two metals. The arrangement of Figure 4 lends itself to quick production; and furthermore 40 this piston may be economically manufactured.

In all cases the disc or annular portion 6 of the depression in the skirt is sufficiently flexibly connected to the rest of the skirt to move as the adjacent body portion of the head, which 45 is secured to it, expands.

What I claim as my invention and desire to 50 secure by Letters Patent of the United States is:—

1. A multi-piece piston having a head, a boss 55 thereon, a tubular skirt, this latter being provided peripherally on one of its non-thrust faces with a substantially flat circular portion through which the skirt is attached to the boss, and a nut and bolt, each of which is locked against turning, for effecting said attachment.

2. A piston, according to claim 1, where the head of the bolt lies against the outer face of the circular portion.

3. A multi-piece piston having a head, a boss 60 thereon, a tubular skirt, said skirt being provided peripherally on one of its non-thrust faces with a substantially flat circular portion through which the skirt is attached to the boss, and a nut and bolt, each of which is locked against 65 turning, for effecting said attachment, said bolt having a hole therein, said piston adjacent the bolt having a mating hole, and a pin engaging in the holes for preventing the bolt from turning.

4. A bi-metallic piston comprising a head of light alloy, wrist-pin bosses integral with the head, a tubular steel skirt provided peripherally with depressions forming substantially flat annular portions, said bosses having annular re- 70 75

cesses about the outer ends thereof confronting the inside of the skirt, said flat annular portions seating in said recesses, and inwardly-extending flanges on the flat annular portions which are 5 co-axial with the wrist-pin bosses.

5. A bi-metallic piston comprising a head, bosses integral with the head, a tubular skirt, a substantially flat annular portion on said tubular skirt, said bosses each terminating at their 10 outer ends in peripheral recesses and said annular skirt portion being received in a recess, and means integral with the flat annular skirt portion and extending inwardly of the bosses for securing the skirt to the bosses.

15. 6. A bi-metallic piston comprising a head, a body part integral with the head, a tubular skirt surrounding said body part, a substantially flat annular portion on the skirt, said body part having a peripheral recess and said annular portion 20 being received in the recess, and means connecting said annular portion to said body part, said means extending inwardly of said body part in the vicinity of the recess therein and the external surface of said annular portion being 25 wholly out of contact with said body part.

7. A bi-metallic piston comprising a head and body of light metal or alloy, said body having co-axial openings for a wrist-pin formed in it, a tubular skirt of steel or cast iron surrounding 30 said body, said skirt being provided peripherally with depressions forming substantially flat an-

nular portions, said body having annular recesses to receive said annular portions, the centers of said annular recesses lying in a longitudinal plane with the axis of said openings, and means uniting said annular portions to said body, the external surfaces of said annular portions being wholly out of contact with said body.

8. A piston, as claimed in claim 7, characterized by each of said means being a tubular flange of said annular portion.

9. A piston, as claimed in claim 7, characterized by each of said means being a frustum-shaped tubular flange of said annular portion.

10. A piston, as claimed in claim 7, characterized by each of said means being a tubular flange 15 of said annular portion, each of said tubular flanges having an outwardly-flared edge within said body.

11. A bimetallic piston comprising a head, a body part integral with the head, a tubular skirt 20 surrounding the body part, the skirt having a substantially flat annular portion merging, at the ends of a diameter, directly into the tubular portion of the skirt and said annular portion also being connected with the tubular portion of the 25 skirt, at the ends of a diameter perpendicular to the first-mentioned diameter, by oppositely-sloping portions, and means connecting said annular portion to the body part.
